UNITED STATES PATENT OFFICE

JOHN CLIFFORD MACLENNAN, OF TORONTO, ONTARIO, CANADA, ASSIGNOR OF ONE-HALF
TO CHRISTOPHER C. THOMPSON, OF TORONTO, CANADA

ANNUNCIATOR

Application filed June 6, 1931. Serial No. 542,585.

The invention relates to improvements in annunciators as described in the present specification and shown in the accompanying drawings which form part of the same.

5 The primary object of the invention is to produce an efficient and reliable annunciator for a street car or other passenger vehicle in order to indicate the names of cross streets of a given route at which the street car stops. 10 The streets are indicated in advance of their being actually reached and to this end the names of the various stops of a particular route are consecutively arranged upon a flexible strip that is wound upon two spools and 15 passed over guide rollers so that the names are individually displayed through a sight as the strip is unwound from one spool and wound upon the other.

If so desired, advertising matter may be 20 carried by the name strip so that the device may also serve as an advertising medium. Furthermore, while in the ensuing description the device is specifically described in its application as an annunciator for a street 25 car, it is also susceptible of use solely as an advertising medium, and therefore it is not intended that the appended claims shall be restricted in this respect.

The distinctive feature of the invention 30 resides in the electro-mechanical operating means for intermittently feeding the name strip in either direction by a single solenoid. This is accomplished by a drum having frictional engagement with the name strip and 35 driven by a ratchet mechanism equipped with a reverse control. The drum has means for turning either of the spools depending upon which spool the strip is being wound.

Referring to the drawings, Figure 1 is a 40 vertical sectional view through a casing illustrating the invention therein contained.

Figure 2 is a horizontal section taken on the line 2—2 of Figure 1.

Figure 3 is a transverse section taken on 45 the line 3—3 of Figure 2.

Figure 4 is a section taken on the line 4—4 of Figure 1 showing the ratchet mechanism for operating the drum.

Figure 5 is a detail of one of the two actuators of the ratchet mechanism.

Figure 6 is an enlarged detail of the manual reverse mechanism of the ratchet.

Figure 7 is a section thereof taken on the line 7—7 of Figure 6.

Figure 8 is a section taken on the line 8—8 of Figure 2 denoting the mechanism for operating one of the spools. 55

Figure 9 is a detail in side elevation of the pawls that actuate the ratchets of the spool actuating mechanism. 60

Figure 10 is an edge view thereof.

Figure 11 is a sectional view of one of the friction clutches and sprockets of the spool actuating mechanism.

Like numerals of reference indicate corresponding parts in each of the figures throughout the drawings. 65

In the drawings in which the preferred construction of the invention is illustrated, the reference numeral 12 denotes the casing for 70 housing the various operating parts; which casing may be of any particular shape or design and has a sight 13 through which the names of streets individually appear as the name strip 14 is intermittently operated. 75 The name strip may consist of a length of fabric or the like, the ends of which are secured to spools 15, 15'. The name strip unwinds from one spool onto the other as the street car is making a trip over a given route; 80 and, as it returns over the route, the direction of feed of the strip is reversed so that the unwinding spool becomes the winding spool and vice versa.

The strip is trained over a drum 16 and 85 guide rolls 17, the latter serving to guide the strip so that the names individually appear through the sight 13. The frictional engagement of the drum drives the strip, and to this end the drum is fixed to a shaft 18 that 90 carries a fixed ratchet 19 having a set of teeth on each side. The teeth 20 on the inner side of the ratchet are used for driving it clockwise, whereas the teeth 21 on the outer side thereof are used for driving it in the opposite 95 direction.

The ratchet is operated by electro-mechanical means comprising a solenoid 23 having conductors 24 for connection in an electric circuit whereby the solenoid is energized by 100

a wiper contact carried by the overhead trolley wire. Said means for operating the solenoid are known in the art and hence do not require further description. The reciprocal core 25 depends from the solenoid and is pivotally attached at 26 to a double toggle mechanism 27. The toggle mechanism is composed of links 28, 28' connecting the core to arms 29, 29', one on each side of the ratchet 19. The arms are pivoted at 30, 30' to respective hubs 31, 31' for lateral swinging movement. Each hub is loosely mounted upon the shaft 18 and provided with a rigid radial member as at 32 that forms a seat for a compression spring 33 that urges the adjacent arm towards the ratchet so that a tooth 34 that it carries will engage the teeth on that side of the ratchet.

In conjunction with the ratchet mechanism a manual control is supplied by which only one arm is engaged with the ratchet at one time. This consists of a substantially U-shaped slide 35 equipped with a handle 35'. The legs 36, 36' are slidably disposed in the wall 37 of the casing 12 parallel with the ratchet shaft 18 and normal to the arms 29, 29'. Each leg carries a rigid finger as at 38, 38'. One of the fingers is disposed in front of the farthest arm 29, while the other finger is disposed at the rear of the nearest arm 29', as best seen from an inspection of Figure 4. The arms are preferably curved as shown.

To operate the manual control, the slide 35 is pulled forwardly so that the finger 38' behind the nearest arm will engage the same and swing it on its pivot 30' away from the ratchet in order to disengage its tooth from the ratchet teeth 21. The slide is locked in this position by conventional means indicated at 39, Figure 6. When it is desired to reverse the ratchet the slide is pushed in so as to cause the finger 38 on the near side of the other arm 29 to engage the same so as to urge it away from the ratchet to disengage it and at the same time the companion arm is released in order that it may engage the ratchet.

From the foregoing description it will be manifest that when the solenoid 23 is energized the core 25, which normally depends under the influence of gravity, is withdrawn into the solenoid. This upward movement causes the links 28, 28' of the toggle mechanism to swing the arms in an upward arc about the axis of the ratchet 19. It will be obvious that since one or the other of said arms is engaged with the ratchet, the ratchet will be turned in a direction depending upon which of the two arms is in engagement with it. As the ratchet turns it rotates the drum 16 so as to frictionally shift the name strip to cause the next name to be displayed in the sight 13.

In order to ensure that the name strip will be tightly wound upon the spools 15, 15', and

also be maintained under proper tension, the spools are provided with driving means so devised that only the spool on which the strip is being wound will be driven. At each operation of the solenoid the driving means tends to turn the winding spool through a greater angle than is required to take up the slack of the strip. This tensions the strip and winds it firmly on the spool, the additional turning movement being accommodated by the interposition of a friction clutch that allows slippage to take place.

This mechanism comprises a radial member 40 keyed to the drum shaft 18 and provided with a pair of pawls 41, 41', one on each side thereof and spring pressed as usual. Upon each side of the radial member 40 is a ratchet 42, 42', the teeth of which are engaged with the respective pawls 41, 41', and oppositely arranged so that when the member 40 is turned in a clockwise direction the pawl 41 will turn the ratchet 42 with it, but the pawl 41' will ride over the ratchet 42'. When, however, the member 40 is turned anti-clockwise the pawl 41' does not operate its ratchet.

Each of these ratchets is connected to mechanism for operating a spool, and as each mechanism is of like construction a description of one will suffice. The ratchet 42' is integral with a sprocket 43 and is loosely mounted upon the shaft 18 therewith. 44 is a chain extending from the sprocket to a sprocket 45 integral with a member 46 of a conventional spring-pressed cone clutch 47, the other member 48 of the clutch being fixed to the shaft 49 of the spool 15'.

Accordingly, when the ratchet 42' is turned by its pawl it simultaneously turns the sprocket 43 and thus the clutch is rotated to wind up the spool and permit lost motion when the tension on the strip 14 becomes excessive.

Whereas the invention has been described in its preferred construction in relation to an annunciator for a street car, it is understood of course that various changes and modifications may be resorted to that come within the scope of the appended claims and that the invention is susceptible of use for annunciators other than the street car type.

What I claim is:—

1. In an annunciator, means for feeding a flexible strip, said means comprising a rotatably mounted drum frictionally engaging the strip, a ratchet having a driving connection therewith, said ratchet having teeth on one side oppositely arranged to teeth on the other side thereof, a pair of tooth members arranged one on each side of the ratchet for engagement with the adjacent teeth thereof, said members being mounted for turning about the ratchet axis and swingable away from its teeth, means for causing either one of the toothed members to engage the ratchet and the other member to simultaneously dis-

engage the ratchet, and electro-mechanical means for oscillating the toothed members.

2. In an annunciator, means for feeding a flexible strip, said means comprising a shaft, a drum fixed thereon and frictionally engaging the strip, a ratchet fixed on said shaft, said ratchet having teeth on one side oppositely arranged to teeth on the other side thereof, a pair of hubs loosely mounted upon the shaft, one on each side of said ratchet, a toothed member yieldably supported by each hub for engagement with the adjacent ratchet teeth, means for causing either one of the toothed members to engage the ratchet and the other member to simultaneously disengage the ratchet, and electro-mechanical means for oscillating the toothed members.

3. In an annunciator, means for feeding a flexible strip, said means comprising a rotatably mounted drum frictionally engaging the strip, a ratchet having a driving connection therewith, said ratchet having teeth on one side oppositely arranged to teeth on the other side thereof, a pair of hubs loosely mounted upon the shaft, one on each side of the ratchet, a radial arm pivoted to each hub for swinging away from the ratchet, a tooth borne thereby for engagement with the adjacent ratchet teeth, spring means for urging each arm toward the ratchet so as to engage its tooth with the teeth thereof, means for swinging either one of the arms away from the ratchet so as to retain its tooth out of engagement with the adjacent ratchet teeth, and electro-mechanical means for oscillating the arms.

4. In an annunciator, means for feeding a flexible strip, said means comprising a rotatably mounted drum frictionally engaging the strip, a ratchet having a driving connection therewith, said ratchet having teeth on one side oppositely arranged to teeth on the other side thereof, a pair of tooth members arranged one on each side of the ratchet for engagement with the adjacent teeth thereof, said members being mounted for turning about the ratchet axis and swingable away from its teeth, springs adapted to urge the toothed members into engagement with the ratchet, a manual control for swinging either one of the toothed members away from the ratchet so as to retain its tooth out of engagement with the adjacent ratchet teeth, and electro-mechanical means for oscillating the toothed members.

5. In an annunciator, means for feeding a flexible strip, said means comprising a rotatably mounted drum frictionally engaging the strip, a ratchet having a driving connection therewith, said ratchet having teeth on one side oppositely arranged to teeth on the other side thereof, a pair of tooth members arranged one on each side of the ratchet for engagement with the adjacent teeth thereof, said members being mounted for turning

about the ratchet axis and swingable away from its teeth, springs adapted to urge the toothed members into engagement with the ratchet, a manually operable slide, a pair of fingers forming a part thereof and arranged transversely of the toothed members so as to engage them in any position of oscillation, said fingers being so arranged that by shifting the slide in one direction one of the fingers releases one of the toothed members from the ratchet and a movement in the opposite direction causes the other finger to similarly release the other toothed members, and electro-mechanical means for oscillating the toothed member.

6. In an annunciator, means for feeding a flexible strip, said means comprising a rotatably mounted drum frictionally engaging the strip, a ratchet having a driving connection therewith, said ratchet having teeth on one side oppositely arranged to teeth on the other side thereof, a pair of tooth members arranged one on each side of the ratchet for engagement with the adjacent teeth thereof, said members being mounted for turning about the ratchet axis and swingable away from its teeth, springs adapted to urge the toothed members into engagement with the ratchet, a reciprocably mounted U-shaped slide, a handle borne thereby, curved fingers rigidly rising from the slide and disposed to urge the toothed members against their spring pressure, and electro-mechanical means for oscillating the toothed members.

7. In an annunciator, means for feeding a flexible strip, said means comprising a rotatably mounted drum frictionally engaging the strip, a ratchet having a driving connection therewith, said ratchet having teeth on one side oppositely arranged to teeth on the other side thereof, a pair of tooth members arranged one on each side of the ratchet for engagement with the adjacent teeth thereof, said members being mounted for turning about the ratchet axis and swingable away from its teeth, means for causing either one of the toothed members to engage the ratchet and the other member to simultaneously disengage the ratchet, a link mechanism connected to the toothed members, and a solenoid adapted to actuate the links so as to oscillate the toothed members.

8. In an annunciator, means for feeding a flexible strip, said means comprising a rotatably mounted drum frictionally engaging the strip, a ratchet having a driving connection therewith, said ratchet having teeth on one side oppositely arranged to teeth on the other side thereof, a pair of tooth members arranged one on each side of the ratchet for engagement with the adjacent teeth thereof, said members being mounted for turning about the ratchet axis and swingable away from its teeth, means for causing either one of the toothed members to engage the ratchet

and the other member to simultaneously disengage the ratchet, a pair of links having corresponding ends attached to the toothed members, and a solenoid having a slidible core attached to the other ends of said links which are so arranged with the toothed members as to compose a double toggle.

9. In an annunciator, the combination with a pair of spools over which a flexible strip is wound that is fed by a friction drum, of an arm rotatable with the drum, a pair of oppositely disposed pawls carried by the arm, a pair of ratchets coaxially mounted with the arm and arranged one on each side thereof, the teeth thereof being oppositely disposed and each ratchet engaged by one of the said pawls, a driving connection between one of the ratchets and a spool, a similar driving connection between the other ratchet and the other spool, and a friction clutch interposed between each driving connection and its spool.

Signed at Toronto, Ontario, Canada, this 11th day of May, 1931.

JOHN CLIFFORD MACLENNAN.
